HOT WATER BOTTLE

Filed July 10, 1925

Fig. 1.

UNITED STATES PATENT OFFICE.

EWALD E. STURK, OF HOLLYWOOD, CALIFORNIA.

HOT-WATER BOTTLE.

Application filed July 10, 1925. Serial No. 42,805.

This invention appertains to hangers for rubber containers, such as hot water bottles, douche bags and the like.

The primary object of the present invention is to provide a novel hanger for rubber containers which can be connected with the containers after the molding thereof and which will effectively prevent the tearing thereof irrespective of the length of use of the container.

Another object of the invention is the provision of a novel hanger for rubber containers embodying a single strip of metal bent back upon itself to provide a pair of gripping jaws for receiving therebetween an enlargement of any desired configuration molded directly upon the container, the jaws being shaped to receive the enlargement and held in firm contact therewith, whereby the displacement of the hanger from the container is precluded.

A further object of the invention is the provision of novel means of forming the hanger for gripping the water bottle and for associating therewith a pivoted eye or loop, whereby the container can readily be hung upon a support, such as a hook or the like.

A still further object of the invention is to provide a hanger for rubber containers such as hot water bottles, douche bags and the like, of the above character, which will be durable and efficient in use, one that will be simple and easy to manufacture and one which can be placed upon the market and incorporated with a rubber container at a small cost.

With these and other objects in view, the invention consists in the novel construction, arrangement and formation of parts, as will be hereinafter more specifically described, claimed, and illustrated in the accompanying drawings, in which drawings:

Figure 1 is a front elevation of a hot water bottle showing the novel hangers associated therewith, the neck of the bottle being shown broken away and partly in section,

* Figure 2 is a detail vertical section taken on the line 3—3 of Figure 1 illustrating the construction of the hanger and the means for associating the same with a container,

Figure 3 is a detail perspective view of the upper end of a container illustrating one form of the enlargement which can be formed thereon for receiving the hanger, and

Figure 4 is a detail fragmentary perspec-

tive view illustrating the neck of a rubber container and showing another form of the enlargement which can be molded thereon for receiving the novel hanger.

Referring to the drawings in detail, wherein similar reference characters designate corresponding parts throughout the several views, the letter A generally indicates a rubber container of the hot water bottle type and B and C the novel hangers or supports therefor.

The hot water bottle A embodies the usual body 10 with the neck 11 at one end and the reduced tab 12 at the opposite end.

In accordance with this invention the neck 11, at one side thereof is provided with an extension or tab 13. The tabs 12 and 13 are formed relatively wide and each have molded thereon an enlargement 14 which may be of any desired configuration without departing from the spirit or scope of the invention. As shown in Figures 1 and 5, the tabs 12 and 13 are provided with elongated substantially cylindrical shaped enlargements 14 which form a gripping bead or rib, as can be readily seen by referring to the said views. As shown in Figure 4, the enlargement or bead, can be undulated or of a serpentine shape, as indicated by the reference character 15. The enlargements extend entirely across the tabs and can be formed in the body of the tabs if preferred.

The hangers B and C are constructed identically the same and therefore only one will be described in detail. Each hanger is formed from a single strip of metal of a non-corrodible type, such as aluminum or the like. The strip 16 is bent back upon itself at a point intermediate its ends, as at 17 to form a pair of spaced parallel body portions 18. The body portions 18 gradually increase in width toward their inner ends and terminate in gripping jaws 19 which are shaped to conform to the configuration of the enlargement formed on the container. As shown in Figure 3 the jaws 19 are bowed transversely as at 20 to receive the cylindrical enlargement or rib. The jaws are clamped in firm engagement with the rib by any suitable means, and as shown, the rivets 21 are passed through the body portions 18.

A suitable eye or loop 22 is carried by the upper end of the strip of metal at the point of molding thereof and the strip is preferably formed to provide a hinge bar-

rel 23 for receiving the said loop or eye to permit the swinging thereof. The loop or eye 22 is provided for permitting the hanging up of the said container and if preferred the body portions 18 can be provided with alined openings 24 to permit the same to be hung up by the strip of metal.

Changes in details may be made without departing from the spirit or the scope 10 of this invention, but:—

What I claim as new is:

1. The combination with a rubber container having a tab at one end provided with an enlargement, of a hanger therefor 15 formed of a single strip of sheet metal bent at a point intermediate its ends back upon itself to provide a pair of companion body portions, the body portions being gradually increased in width toward their 20 inner ends, a pair of companion gripping jaws formed on the inner ends of the body portions for receiving the enlargement, rivets passing through the body portions for holding said body portions in contact 25 with each other and the jaws in gripping engagement with the enlargement, and a swinging loop carried by the outer end of the hanger.

2. The combination with the rubber container having a tab at one end provided 30 with a rib extending entirely across the

same, of a hanger for the container constructed of a single strip of sheet metal folded back upon itself at a point intermediate its ends including a pair of companion body portions and a pair of gripping jaws shaped to conform to the configuration of the bead, the jaws extending entirely across the body portions, means connecting the body portions in contact with one another, a barrel formed on the outer end of the hanger, and a loop rockably mounted within said barrel.

3. The combination with a container having a tab provided with a cylindrical rib 45 extending entirely across the same, of a hanger for the container constructed from a single sheet of non-corrodible metal folded back upon itself to provide a pair of companion body portions, companion gripping jaws formed on the inner ends of the body portions, said gripping jaws being bowed transversely to receive said bead, the strip of metal at the point of folding thereof being bowed to provide a hinge barrel, a loop rockably carried by the barrel, and rivets passing through the body portions to hold the same in contact with one another and the jaws in gripping engagement with the bead.

In testimony whereof I affix my signature.

EWALD E. STURK.
